UNITED STATES PATENT OFFICE

110,861

DESIGN FOR AN ANIMAL FIGURE

Charles H. Forbell, Bayside, Long Island, N. Y.,
assignor to Rogers Peet Company, New York,
N. Y., a corporation of New York

Application June 6, 1938, Serial No. 77,635

Term of patent 14 years

To all whom it may concern:

Be it known that I, Charles H. Forbell, a citizen of the United States, residing at Bayside, Long Island, New York, have invented a new, original, and ornamental Design for Animal Figures, of which the following is a specification, reference being had to the accompanying drawing, forming a part thereof.

I claim:

The ornamental design for an animal figure, as shown.

CHARLES H. FORBELL.
